UNITED STATES PATENT OFFICE.

JAMES A. PETRIE, OF MINNEAPOLIS, MINNESOTA.

CAN OPENER.

Application filed December 15, 1921. Serial No. 522,568.

To all whom it may concern:

Be it known that I, JAMES A. PETRIE, a citizen of the United States, resident of Minneapolis, county of Hennepin, State of Minnesota, have invented certain new and useful Improvements in Can Openers, of which the following is a specification.

The object of my invention is to provide a can opener which will lie close to the end of the can and be supported in such a way that it can not rock or slip out of position while in use.

A further object is to provide a can opener of strong, durable construction and one which can be easily and quickly adapted for opening large or small cans.

The invention consists generally in various constructions and combinations, all as hereinafter described and particularly pointed out in the claims.

In the accompanying drawings forming part of this specification,

Figure 1 is a plan view of a portion of a can, showing my invention applied thereto, Figure 2 is a detail sectional view of the same,

Figure 3 is a sectional view on the line 3-3 of Figure 1.

In the drawing, the frame of the opener is preferably formed by bending a metal rod to provide side rails 2 and a connecting curved end portion 3. The rails are in parallel relation and are comparatively stiff and rigid and capable of withstanding considerable downward pressure thereon without bending. The ends of the rails are preferably held in parallel relation by suitable means, such as a cross bar 4, and a tongue 5 secured at 6 to the cross bar and having ends fitting within notches 7 in the rails, the bar 4 having preferably holes therein through which the ends of the rails are inserted. This means of fastening the rails in parallel relation may, however, be modified in various ways.

At the opposite end of the rails at the point where they are joined together by the curved portion 3 I provide a steel pointed pin 8 that is adapted to be thrust through the top of the can preliminary to the operation of opening. This pin is curved, as shown, so that when it is thrust through the top of the can, the frame of the opener can be tilted down to a substantially horizontal position, resting upon the cover of the can.

Upon the rails 2 I provide a carriage or slide consisting of plates 9 arranged in parallel relation and connected by suitable means, such as cross bars 10, which hold the plates in their proper relative position while allowing them to move freely back and forth on the rails. I have shown a shaft 11 mounted in these plates and on this shaft I arrange a cutting wheel 12 having a thin edge which projects below the slide and is adapted to engage and cut the cover.

To hold the frame from premature movement on the rails I prefer to provide a second wheel 13, shown in the drawing as integral with the wheel 12, the two forming a spool, but in practice I may prefer to make this wheel 13 independently of the wheel 12. The wheel 13 is of smaller diameter preferably than the wheel 12, there being an annular gap between them to receive the edge of the can, and while the wheel 12 is cutting the cover, the other wheel depends on the outside of the can and in case of slippage of the slide on the rails, would contact with the can. Generally, however, the rails will rest on the edge of the can and slide thereon as the tool is used, while the hub of the wheels will be spaced from the edge of the can. The bearing of the rails in the front and rear of the wheels prevents the tool from tilting or turning in the hand and aids materially in using the device.

I am aware that can openers of somewhat similar type have been known heretofore. I do not, therefore, claim broadly the idea of the pin thrust through the top of the can and the cutting wheel riding on the surface of the cover, my invention consisting primarily in the rigid side rails whereon the wheel slide or support is mounted, and the guide for the cutting wheel.

I claim as my invention:

1. A can opener comprising a rod bent to form parallel side rails and a curved connecting portion between them at one end adapted to overhang the top of the can, a pin mounted in said curved connecting portion for insertion through the top of the can, a slide carriage mounted on said rails to move freely back and forth thereon, said slide comprising parallel plates having holes therein to loosely receive said rails, cross-bars connecting said plates, a spool centrally mounted in said carriage and having a cutting wheel at one end to engage the surface

of the cover, and a guiding wheel at its other end to depend outside the walls of the can, the middle portion of said wheel being adapted to ride on the peripheral edge of the can, said rails when the opener is in use having a bearing on the edge of the can in front of and in the rear of said spool and between the plates of said carriage.

2. A can opener comprising a frame having a pin at one end for insertion through the can cover and provided with rigid, substantially parallel side rails, a slide carriage mounted for freedom of movement on said rails to adapt the device for cans of dif-

ferent diameter, a spool mounted in said slide and having a cutting wheel at one end to engage the top of the can, and a guide wheel at its other end to depend outside the walls of the can and said rails when the device is in use, riding on the edge of the can in front of and in the rear of said wheel and between the walls of said carriage and preventing the implement from rocking or twisting under pressure on the cutting wheel.

In witness whereof, I have hereunto set my hand this 9th day of December, 1921.

JAMES A. PETRIE.
